UNITED STATES PATENT OFFICE.

JOHN B. HADAWAY, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

TACK PULLING AND RESETTING MACHINE.

1,109,220.

Specification of Letters Patent.

Patented Sept. 1, 1914.

Application filed December 28, 1911. Serial No. 668,341.

To all whom it may concern:

Be it known that I, JOHN B. HADAWAY, a citizen of the United States, residing at Swampscott, in the county of Essex and 5 State of Massachusetts, have invented certain new and useful Improvements in Tack Pulling and Resetting Machines; and I do hereby declare the following to be a full, clear, and exact description of the invention, 10 such as will enable others skilled in the art to which it appertains to make and use the same.

The present invention relates to machines for preparing lasted boots and shoes for the 15 sewing operation and more particularly to that type of machine which is employed for removing lasting tacks from a boot or shoe and inserting holding tacks in place thereof. Machines of this general type operate upon 20 the shoe preparatory to the sewing operation to remove lasting tacks and insert a fewer number of holding tacks which serve to retain the upper in its lasted position during the sewing operation without interfering 25 ence with the needle of the sewing machine. As the tack pulling mechanism of this machine is actuated continuously it is conducive to the efficient operation of the machine that this mechanism be of a simple and compact construction having a small number of 30 moving parts which are not subject to constant breakage and which are free from complicated movements tending to increase the difficulty of properly adjusting the machine.

The object of the present invention is to provide an improved machine of this character having a simple and compact arrangement of parts which operate smoothly and 40 quietly and which removes the lasting tacks with great rapidity and inserts the requisite number of holding tacks with precision and certainty.

With this object in view, one feature of 45 the invention consists in the combination of a rotary tack pulling tool operating in the line of feed of the shoe and continuously actuated during the operation of the machine and a tack driving plunger supported 50 in close proximity to the tack pulling tool and under the control of the operator to insert the holding tacks at irregular intervals along each side of the shoe.

A further feature of the invention consists 55 in the combination of a rotary tack

pulling tool having a tack engaging blade with a coöperating stationary jaw which has provision for a yielding movement away from the tack pulling tool.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention:—Figure 1 represents a front elevation of a machine embodying the several features of the invention in their preferred forms; Fig. 2 is a left hand side elevation of the machine shown in Fig. 1; Fig. 3 is a transverse section taken upon the line 3—3 of Fig. 1 and looking in the direction of the arrows; Fig. 4 is a detail illustrating the relative positions of the tack pulling tool and tack driving plunger and the means for positioning the tack to be removed in the proper operative relation to the tool; Fig. 5 is a detail illustrating a cross section of the downholds and tack pulling tool and showing the manner in which the tack is positioned relative to the tool; and Fig. 6 is a detail partially diagrammatic illustrating the manner in which the tack is removed from the shoe.

The machine shown in the illustrated embodiment of the invention consists of a tack driving mechanism and a tack pulling mechanism located adjacent to one another in the direction or line of feed of the shoe in order that each side of the lasted shoe may be fed continuously along in one direction to remove the lasting tacks and insert the requisite number of holding tacks. The tack driving nozzle is located in the line of feed of the shoe in close proximity to the tack pulling mechanism in order that the lasting tack may be removed and a holding tack inserted in place thereof at substantially the same point without varying the position of the shoe relative to the machine.

As is usual in this type of machine the tack driving mechanism is under the control 105 of the operator and is constructed and arranged to drive only a single tack upon each depression of the operating treadle. The tack driving plunger is normally held in a raised or inoperative position by a suit-

able trip mechanism but is released upon depressing the treadle to allow an actuating spring to impart a downward blow to the plunger. The machine as a whole is mounted upon a suitable frame indicated at 1 and is operated by a main driving pulley 2 journaled in the upper portion of the machine frame. The tack driving mechanism is provided with a plunger 3 which operates through a nozzle 4 and to which a working blow is imparted by an actuating spring 5. The plunger is normally held in a raised position by an elevating cam 6 which is mounted upon the outer end of a shaft 7 and is rotated by the engaging of two clutch faces formed respectively upon the pulley 2 and a clutch member 8. The pulley 2 is moved into operative engagement with the clutch member 8 by an arm 9 pivoted at its lower end to the frame of the machine and connected at its upper end to a tension spring 10. The clutch faces are normally held out of engagement by a latch lever 11 which is supported upon an arm 12 actuated by a path cam 13. The cam is secured to the shaft 7 and is designed to move the lever 11 and disengage the clutch members upon the completion of a single revolution of the shaft. When the clutch members are disengaged, the rotation of the shaft 7 is stopped and the elevating cam holds the plunger raised. The lever 11 is maintained in engagement with a block 14 by a spring 15 and is depressed to allow the actuation of the plunger by a dog 16 connected to the operating treadle. The cam 13 is arranged to remove the lever 11 from engagement with the dog 16 before the shaft 7 has completed its revolution in order that the lever 40 may be positioned properly to engage with the block 14 irrespective of the position of the treadle. In order to stop the rotation of the shaft 7 immediately, a suitable form of friction brake indicated at 18 is provided. The trip mechanism has been only briefly described herein as it forms no part of the present invention and is substantially the same as the trip mechanism shown and described in the patent to Woodward, 389,275, 50 September 11, 1888.

It is desirable in machines of this type to provide a tack pulling mechanism which may be operated continuously at a high speed without a constant breakage of parts or otherwise detracting from the efficiency of the machine. In order to accomplish this result it is necessary to provide a tack pulling mechanism which has a relatively small number of parts, free from complicated movements, and which operates smoothly and quietly both when engaged in removing tacks and when running idle. To this end the tack pulling mechanism of the present invention consists of a tack pulling tool operating in the line of feed of the shoe and

which is secured upon the end of a shaft journaled in rigid bearings and continuously actuated during the operation of the machine. It is desirable that the tacks which have been removed from the shoe be ejected away from the operator toward the rear of the machine and that the various elements of the tack pulling mechanism be arranged in a manner to allow the free manipulation of the shoe by the operator when feeding the same. To this end the shaft to which the tack pulling tool is secured is arranged obliquely to the line of feed of the shoe and the tack pulling movement takes place in a rearward direction. The tack is supported against the lateral thrust of the tool and is retained in engagement with the tool by a stationary jaw which has provision for a yielding downward movement to prevent breakage of the operating parts of the machine when a tack of unusual size is encountered. The upper of the shoe upon opposite sides of the lasting tacks to be removed is pressed down by a pair of downholds, the adjacent edges of which form a throat for guiding the tack into a position of presentation relative to the tack pulling tool. In the simplest and most efficient form of the invention which has yet been devised, one of the downholds constitutes a stationary jaw or thrust plate for supporting the tack against the thrust of the tack pulling tool and insuring the positive engagement and removal of the tack by the tool.

The tack pulling tool is indicated at 20 and is secured upon the outer end of a shaft 22 journaled obliquely in bearings 23 and 24, as shown clearly in Fig. 3. The bearings for the shaft 22 are formed upon a bracket 25, adjustably secured to the machine frame by bolt and slot connections indicated at 26 and 27 respectively and by means of this adjustment the tack pulling tool may be readily positioned in the proper operative position relative to the tack driving mechanism. The shaft 22 is continuously rotated during the operation of the machine by a driving belt 28 which operatively connects a drive pulley 29 with a driven pulley 30 fastened to the shaft 22. The belt 28 is guided in its course by an idler pulley 31 journaled upon an arm 32 and an idler pulley 33 journaled upon an arm 35. The supporting arms 32 and 35 of the idler pulleys are adjustably mounted upon the bracket 25 in order to vary the position of the pulleys and to increase or decrease the tension upon the belt. In order to manipulate the tack pulling tool by hand, if so desired, a handwheel 37 is mounted on the rear end of the shaft 22 as shown clearly in Figs. 1 and 3.

The tack pulling tool shown in the illustrated embodiment of the invention is provided with a single tack pulling blade 40 which has a transverse tack engaging edge 130

arranged to engage with the shank of a lasting tack beneath the head. The upper of the shoe is engaged upon opposite sides of the lasting tack to be removed by a pair of 5 downholds indicated respectively at 45 and 46, the adjacent edges of which form a throat for guiding the tacks into position to be removed by the tack pulling tool. The downhold 46 is adjustably secured to the 10 machine frame by a bolt 47 in order that the downhold may be positioned in the proper relation to the tack pulling tool and coöperating downhold. The tacks are positioned laterally of the tool by a transverse 15 abutment which consists of an upstanding rib 48 formed integral with the downhold and projecting into the path of the tack to be removed, as shown clearly in Fig. 4. The downhold 45 is formed upon the outer end 20 of an I-shaped bracket 41 which is adjustably secured to a slide 42 by means of a bolt and slot connection indicated at 43. The slide 42 is pivoted upon a supporting member 50 at 51 and a spring 52 interposed be- 25 tween the lower end of the slide and the supporting member serves to normally retain the downhold in operative relation to the tool. The normal position of the downhold is determined by a stop member consisting 30 of a screw 55 threaded in the bracket 41 and engaging with the under side of the machine frame. The member 50 is supported upon the bracket 25 and has provision for a lateral adjustment relative thereto by a bolt and 35 slot connection indicated at 56. It will thus be obvious that with the above described construction the downhold has provision for an universal adjustment relative to the tool and that in operation the downhold may be 40 depressed when a tack of an unusual size is engaged between the downhold and tack pulling tool. As shown clearly in Figs. 5 and 6, the downhold 45 supports the tack against the thrust of the tool when it en- 45 gages therewith and holds the tack in engagement with the tool throughout the en-

tire range of the tack pulling movement, thus providing a stationary jaw which co- operates with the tack pulling tool.

While it is preferred to employ the specific 50 construction and arrangements of parts shown and described, it will be understood that this construction and arrangement is not essential except so far as specified in the claims and may be changed or modified 55 without departing from the broader features of the invention.

Having thus described the invention, what is claimed is:—

1. A tack pulling and resetting machine 60 having, in combination, a tack driving plunger, means under the control of the operator for imparting a working stroke to the plunger, a rotary tack pulling tool having its axis arranged obliquely to the line of feed of 65 the shoe, and means for continuously actuating the tack pulling tool, substantially as described.

2. A tack pulling and resetting machine 70 having, in combination, a rotary tack pull- 75 ing tool arranged to have a tack pulling movement in a rearward direction, means for actuating the tool, a tack driving plunger located adjacent to the tack pulling tool and operating in the line of feed of the shoe, and means under the control of the operator for imparting a working stroke to the plunger, substantially as described.

3. A tack pulling and resetting machine 80 comprising a rotary tack pulling tool ar- 85 ranged to operate in the line of feed of the shoe, mechanism for actuating the tool trans- versely to the line of tacks, and a stationary jaw arranged to support the tack against the thrust of the tack pulling tool and hav- 85 ing provision for a yielding movement away from the tool, substantially as described.

Correction in Letters Patent No. 1,109,220.

It is hereby certified that in Letters Patent No. 1,109,220, granted September 1, 1914, upon the application of John B. Hadaway, of Swampscott, Massachusetts, for an improvement in "Tack Pulling and Resetting Machines," an error appears in the printed specification requiring correction as follows: Page 3, line 20, for the compound word "I-shaped" read *L-shaped*; and that the said Letters Patent should be read with this correction therein that the same may conform to the record of the case in the Patent Office.

Signed and sealed this 6th day of October, A. D., 1914.

[SEAL.]

R. F. WHITEHEAD,
Acting Commissioner of Patents.
